UNITED STATES PATENT OFFICE.

EBEN C. SPEIDEN, OF NIAGARA FALLS, NEW YORK, ASSIGNOR TO INTERNATIONAL ACHESON GRAPHITE COMPANY, OF NIAGARA FALLS, NEW YORK, A CORPORATION OF NEW JERSEY.

COMPOSITE ELECTRODE.

1,032,250.

Specification of Letters Patent.

Patented July 9, 1912.

Application filed May 17, 1910. Serial No. 561,649.

To all whom it may concern:

Be it known that I, EBEN C. SPEIDEN, a citizen of the United States, residing at Niagara Falls, in the county of Niagara and 5 State of New York, have invented certain new and useful Improvements in Composite Electrodes, of which the following is a specification.

This invention relates to electrodes designed particularly for electrothermic work, as for example the production of steel or other metallic products in the electric furnace. For such purposes carbon electrodes, either graphitic or non-graphitic, are commonly employed, and these are often of very large dimensions. With such electrodes however the unit cost of manufacture increases with the size above a certain limit, and it becomes moreover increasingly difficult to secure uniformity between the units and homogeneity of each unit. Hence it often occurs that the larger sizes of electrodes are of inferior quality, and a cheaper and better electrode may be made by assembling a plurality of individual pieces, bars or plates in conductive relation to each other. It is further often desirable in electrothermic work that the electrode should be so constructed that it may be fed continuously to the furnace in proportion as it is consumed, and for this purpose it is common to machine the ends of the electrodes in such manner that new lengths may be added as required.

According to the present invention a plurality of bars or plates of graphitic or non-graphitic carbon, or of other suitable electrode material, are assembled to form a composite electrode, the manner of assembling the bars being such as to secure a high degree of electrical conductivity in the composite electrode, and to enable the electrode to be fed forward as desired by the addition thereto of the constituent bars or plates. 40 This construction presents an important advantage in that it affords a joint of good electrical conductivity and mechanical strength without the necessity of machining the ends of the sections. The electrodes may be constructed of rectangular bars of carbon or graphite of standard form and dimensions, the conformation required to provide a joint being secured by assembling these standard bars in a certain definite longitudinal relation to each other.

For a full understanding of the invention reference is made to the accompanying drawings wherein—

Figure 1 is a perspective view of the initial working end of an electrode; Fig. 2 60 is a transverse section on the line II—II of Fig. 1; Fig. 3 is a perspective view of an electrode, showing the manner of building up the members; and Fig. 4 is a longitudinal section illustrating a modified form of joint. 65

Referring to the drawings, the electrode is illustrated as consisting of four laterally juxtaposed rectangular bars 1, 2, 3, 4. Of these bars, that numbered 1 is the shortest, 2 somewhat longer, 3 longer than 2, and 4 70 the longest. These bars are secured together laterally in conductive relation, preferably by means of carbon or graphite pins 5, and together constitute what may be described as the initial working end of the electrode. 75

In alignment with the bars 1, 2, 3, 4, are disposed bars 1^a, 2^a, 3^a, 4^a, of similar section, the last-mentioned bars being of uniform length and secured together and to the bars constituting the initial working end of the 80 electrode by transverse pins 5 or otherwise in such manner as to produce a mechanically strong composite block. By reason of the staggered relation of the joints the composite electrode possesses at all transverse 85 sections an electrical conductivity which fairly approximates its maximum conductivity.

In the construction illustrated in Figs. 1 and 3 the ends of the aligned bars merely 90 abut, a filling of powdered graphite or graphitic cement being interposed if desired to improve the conductivity of the joint. Or the conductivity may be improved by increasing the surface of contact at the joints 95 in any preferred manner; for example the bars may be provided with projections 6 adapted to engage recesses 7 in the ends of the adjacent bars, as illustrated in Fig. 4.

In use the current is conveyed to the composite electrode by means of any suitable terminal adjustable thereon, as indicated by way of example at 8 in Fig. 4. As the electrode is consumed the position of the terminal is shifted, additional bars being applied 105 and secured as the operation proceeds.

While I have illustrated a composite electrode composed of four parallel members, each member consisting of any desired number of aligned bars, it is to be understood that 110

the invention is not restricted to any particular number of members, as these may be multiplied as desired in order to make a composite electrode of the desired section 5 from units of any convenient dimensions.

I claim:—

1. An electrode consisting of a plurality of prismatic members of electrically conductive material assembled in conductive relation to each other, the said members terminating in different planes, whereby additional members of like form may be added 10 as required.
2. An electrode consisting of a plurality

of prismatic members of electrically conductive material assembled in conductive relation to each other, the said members terminating in different planes, whereby additional members of like form may be added as required, in combination with a terminal 20 adjustable on the electrode.

In testimony whereof, I affix my signature in presence of two witnesses.

EBEN C. SPEIDEN.
